Patented Sept. 26, 1916.

UNITED STATES PATENT OFFICE.

JOHN C. KNOKE, OF MARICOPA, CALIFORNIA.

WELL-TUBING DUMP.

1,199,190.

Specification of Letters Patent. Patented Sept. 26, 1916.

Application filed November 1, 1915. Serial No. 59,019.

To all whom it may concern:

Be it known that I, JOHN C. KNOKE, a citizen of the United States, residing at Maricopa, in the county of Kern and State 5 of California, have invented certain new and useful Improvements in Well-Tubing Dumps, of which the following is a specification.

My invention relates to well pumping machinery, and more particularly to a device 10 to be used in connection with deep well pumps, to facilitate the removal thereof from the well under certain abnormal conditions as hereinafter described. The device is 15 equally applicable in water or oil wells, but since the conditions necessitating its use are more prevalent in oil wells, it will be described herein with particular reference to such wells.

20 The usual type of deep well pump is so constructed that, under normal conditions, when it is desired, for any reason, to remove the tubing and the working barrel connected thereto from the well, the valves and plunger 25 may first be drawn out of the tubing by means of the string of sucker rods. This allows the fluid in the tubing to drain back into the well, whereupon said tubing may be more easily hauled up. In the operation 30 of oil wells, however, great quantities of sand are often produced with the fluid and are very troublesome. One difficulty often experienced is that caused by the sand filling and clogging the working barrel and lower 35 end of the tubing, necessitating the removal of the tubing from the well in order to clear the working barrel and render it operative. This is called "sanding up" and when a pumping well is in this condition it is not 40 possible to pull up the standing valve with the plunger, by means of the sucker rods, in the usual way and allow the fluid in the tubing to flow back into the well. The usual practice in the case of a well "sanding up" 45 is to pull the string of tubing out of the well, unscrewing sections of about 60 feet long as the tubing is brought to the surface. As each section is unscrewed the fluid contained in the same flows out over the 50 derrick floor and sprays the operators, causing much discomfit and wasting considerable valuable fluid. Moreover, a string of tubing full of oil is very much heavier than it would otherwise be, thus requiring additional power to hoist it out of the well.

The object of the present invention, there-

fore, is to provide a means whereby the tubing may be drained of the fluid contained therein, and the sucker rods removed, when the working barrel is rendered inoperative 60 by being clogged with sand or otherwise, in order to facilitate the removal of said working barrel and said tubing, from the well.

To this end my invention consists in the 65 novel well-tubing dump hereinafter described with reference to the accompanying drawings, in which—

Figure 1 is a longitudinal sectional view of the well-tubing dump in closed, or normal position. Fig. 2 is a similar view to Fig. 1, except that the dump is shown in open position and the sucker rods disjoined, and ready for removal.

1 and 2 represent two adjacent sections of 75 well-tubing-string. It is to be understood that a pump of the usual deep-well type, not shown in the drawings, is located at the lower end of the tube section 1. The two sections 1 and 2 are united by a special form 80 of coupling 3, having an interior tapered bore or seat 4, of slightly less diameter than the interior of the tubing 1 and 2, and provided with an opening 5 through the wall thereof. A substantially cylindrical sleeve 85 or plunger-valve 6, having an exterior tapered portion 7 adapted to seat within the coupling 3, and to close the opening 5 when so seated, is placed within the tubing section 2 and normally allowed to seat itself by 90 gravity within said coupling 3, as shown in Fig. 1.

The sucker rod section 8, attached at its lower end to the pump plunger, not shown in the drawings, is joined to an adjacent section 9 at a point slightly below the seat-coupling 3 in the tubing, by means of a special coupling consisting of two members 10 and 11, fastened respectively to the sucker rod sections 8 and 9 by the usual 95 right-hand threaded joints 12 and 13, but connected to each other by a left-hand threaded joint 14, said joint being the only one in the entire string of sucker rods provided with a left-hand thread.

The outside diameter of the coupling member 11 is greater than the inside diameter of the plunger valve 6. In the normal operation of the pump, said coupling 11 does not come in contact with said plunger valve 6. But when the pump becomes 100 clogged as by the "sanding up" of the

well, the coupling members 10 and 11 may be separated by turning the entire string of sucker rods to the right, by means of the uppermost section thereof. The string of 5 sucker rods, thus freed from the stuck pump plunger, may then be drawn up out of the tubing. In so doing, the coupling member 11, engaging the plunger valve 6, lifts the same off its seat 4, as shown in Fig. 10 2, and carries it up through the tubing. This uncovers the opening 5 in the seat-coupling 3, through which opening the fluid contained in the tubing drains back into the well, and said tubing may be readily hauled 15 up out of the well.

I have herein described my device in the form which is deemed preferable. I am aware, however, that changes may be made without departing from the spirit of the invention, and I therefore do not wish to be construed as limiting myself in this regard.

I claim:—

1. A well-tubing dump for deep well pumps comprising a section let into the 25 tubing string above the working barrel of the pump and provided with an opening through its wall; a freely floating valve member seated in said section and normally covering said opening; and means carried 30 by the sucker-rod string above the pump plunger for engaging said valve member to uncover said opening as said sucker-rod string is withdrawn through the tubing string.

2. A well-tubing dump comprising a section let into the tubing string and provided with an opening through its wall; a valve member seated in said section and normally covering said opening; means for disjointing 40 the sucker-rod string to enable it to be withdrawn through the tubing string; and means on said sucker-rod string engaging said valve member to uncover said opening as the disjointed sucker-rod string is withdrawn.

3. A well-tubing dump comprising a section let into the tubing string and provided with an opening in its wall; a hollow plunger-valve adapted to seat within said section 50 to close said opening; and a separable coupling member in the sucker-rod string adapted to engage the hollow plunger-valve and lift it to uncover the opening in the wall of said tubing section.

4. A well tubing dump comprising tubing having a seat formed in its interior and an opening through its wall in proximity to said seat; a hollow plunger-valve adapted to normally rest upon said seat to close said 60 opening; and a separable coupling member in the sucker-rod string adapted to engage the hollow plunger-valve and lift it to uncover said opening in the tubing wall.

5. A well tubing dump comprising tubing having a seat formed in its interior and an

opening through its wall in proximity to said seat; a hollow plunger-valve adapted to normally rest upon said seat to close said opening; means carried by the sucker-rod string for engaging with said plunger-valve to raise the same to uncover said opening in the tubing wall; and means for disjointing said sucker-rod string at a point below said plunger-valve engaging means.

6. A well tubing dump comprising a sleeve 75 section connecting the ends of adjacent sections of the tubing-string and provided with an opening in the wall thereof; a hollow plunger-valve adapted to seat within said sleeve to close said opening; means carried by the sucker-rod string for engaging with said plunger-valve to raise the same to uncover said opening; and means for disjointing said sucker-rod string at a point below 80 said plunger-valve engaging means.

7. A well tubing dump comprising a sleeve section connecting the ends of two adjacent sections of the tubing-string, said sleeve section having an interior annular tapering seat and an opening in its wall in proximity to said seat; a hollow plunger-valve having a taper portion adapted to rest within said seat to normally close said opening; means carried by the sucker-rod string for engaging with said plunger-valve to raise the same to uncover said opening; and means for disjointing said sucker-rod string at a point below 90 said plunger-valve engaging means.

8. A well tubing dump comprising a sleeve 100 section connecting the ends of two adjacent sections of the tubing-string, said sleeve section having an interior annular tapering seat and an opening in its wall in proximity to said seat; a hollow plunger-valve having a taper portion adapted to rest within said seat to normally close said opening; a separable coupling member for joining the ends of two adjacent sections of the sucker-rod string, said coupling member being 105 adapted to engage said hollow plunger-valve to raise the same to uncover said opening.

9. A well tubing dump comprising a sleeve section connecting the ends of two adjacent sections of the tubing-string, said 115 sleeve section having an interior annular tapering seat and an opening in its wall in proximity to said seat; a hollow plunger-valve having a taper portion adapted to rest within said seat to normally close said opening; and a separable coupling for joining the ends of two adjacent sections of the sucker-rod string consisting of two members, each provided with a right-hand screw-thread for attachment to one of said rod ends, and inter-engaging left-hand screw-threads for coupling said members together, one of said members being of such diameter 120 as to engage said hollow plunger to lift the same to uncover said opening.

10. A well-tubing dump comprising a sleeve section let into the tubing string and provided with an opening through its wall; a plunger valve seated within said section
5 and normally covering said opening; and a separable coupling for joining the ends of two adjacent sections of the sucker-rod string consisting of two members, each provided with a right-hand screw-thread for
10 attachment to one of said rod ends, and inter-engaging left-hand screw-threads for

coupling said members together, one of said members being of such diameter as to engage said hollow plunger to lift the same to uncover said opening. 15

In testimony whereof I have signed my name to this specification in the presence of two subscribing witnesses.
